(57) **CLAIM**

The ornamental design for an insertable drink holder system, as shown and described.

DESCRIPTION

FIG. 1 is a front view of an embodiment of the insertable drink holder system;

FIG. 2 is a back view of an embodiment of the insertable drink holder system;

FIG. 3 is a left view of an embodiment of the insertable drink holder system;

FIG. 4 is a right view of an embodiment of the insertable drink holder system;

FIG. 5 is a top view of an embodiment of the insertable drink holder system;

FIG. 6 is a bottom view of an embodiment of the insertable drink holder system; and,

FIG. 7 is a perspective view of an embodiment of the insertable drink holder system.

1 Claim, 4 Drawing Sheets
